Design for Double Library Shelf

DES. 1991

Wm B. Satte of Hartford, Conn.

Letters Patent No 1991-Dated Sept 27th 1863.

Design for a Double Lamp Stove.

The same to be referred to in these Letters Patent and making part of the same.

To all whom it may concern:

Be it known that I, William B. Satte, of the City and County of Hartford and State of Connecticut, have invented or produced a new and original Design for Double Lamp Stove; and I do hereby by declare that the following is a full and exact description of the same, reference being had to the illustrations in which the same letters indicate the parts in each of the figures.

The accompanying drawing is a perspective view of my design in which α is a double stove body, β are the lids, γ are the legs, δ are the smoke pipe, ϵ are the lamps.

What I claim therefore and desire to secure by Letters Patent is, & the stove in the double lamp stove substantially as illustrated and as enclosed.
